8411 X Hermann H. Glavis Hamburg, N.Y.

Setters Patent.

The Schedule referred to in these Letters Patent and making part of the same, containing a description in the words of the said Herman Miller himself of his improvement in making Sun Dials, called the Cast Iron Sun Dial.

To all persons to whom these presents shall come,
Herman Melier of Flamburgh in the County of Erie State of
New York, sends greeting. Be it known that the said Herman
Melier have invented, constructed made and applied to
use, a new and useful improvement in making sun-Dials,
called the Cast Iron Sun-Dial, Specified in the words following.
The Dial is of the common form with the improvement of
being made of cast iron and of a large size sufficient for re-
gulating Clocks and Watches, which improvement is all that
I claim as my invention; (Now there are many kinds of sun
Dials, such as east or perpendicular plates facing North
or South or East or West, but the horizontal plated Dials
are most in use and considered preferable to any other, they
are generally made with a round horizontal plate, with a
flat gnomon or stile standing perpendicular, and due North
from the center of the plate, or near there) with the upper edge
of said stile, pointing directly at the North pole, a pole star,
with hour lines drawn on the horizontal plate to agree with
the shadow of the stile at the hours designated)

In testifying that the above is a true specification of my said improvement as above described, I have hereunto set my hand this twenty-first day of July 1834.
